US0D1103385S

(12) **United States Design Patent** (10) **Patent No.:** **US D1,103,385 S**
(45) **Date of Patent:** **** Nov. 25, 2025**

(54) **CUT GUIDE**

(71) Applicant: **Paragon 28, Inc.**, Englewood, CO (US)

(72) Inventors: **Kyle James Hartson**, Denver, CO (US); **Albert Dacosta**, Lone Tree, CO (US); **Randy Allard**, Golden, CO (US)

(73) Assignee: **Paragon 28, Inc.**, Englewood, CO (US)

(**) Term: **15 Years**

(21) Appl. No.: **29/946,625**

(22) Filed: **Jun. 10, 2024**

Related U.S. Application Data

(63) Continuation of application No. 18/327,049, filed on May 31, 2023, which is a continuation of application No. 16/508,955, filed on Jul. 11, 2019, now Pat. No. 11,690,660, which is a continuation of application No. PCT/US2019/041146, filed on Jul. 10, 2019, application No. 29/946,625 is a continuation of application No. 29/876,872, filed on May 30, 2023, now Pat. No. Des. 1,034,985, which is a continuation of application No. 29/826,424, filed on Feb. 11, 2022, now abandoned, which is a continuation of application No. 29/710,821, filed on Oct. 25, 2019, now Pat. No. Des. 943,741, which is a continuation of application No. 29/655,887, filed on Jul. 9, 2018, now Pat. No. Des. 865,173.

(57) **CLAIM**

The ornamental design for a cut guide as shown and described.

DESCRIPTION

FIG. 1 is a front, top perspective view of the cut guide comprising the new design;

FIG. 2 is a back, bottom perspective view of the design of FIG. 1;

FIG. 3 is a front elevational view of the design of FIG. 1; FIG. 4 is a back elevational view of the design of FIG. 1; FIG. 5 is a top view of the design of FIG. 1;

FIG. 6 is a bottom view of the design of FIG. 1;

FIG. 7 is a right elevational view of the design of FIG. 1; and,

FIG. 8 is a left elevational view of the design of FIG. 1. The evenly spaced broken lines immediately adjacent to the claim and the dot-dot-dash broken lines represent the bounds of the claimed design while all other evenly spaced broken lines are directed to environment and are for illustrative purposes only; the broken lines form no part of the claimed design.

1 Claim, 6 Drawing Sheets
